UNITED STATES PATENT OFFICE.

GEORGE H. WOODMAN, OF NEW YORK, N. Y.

PNEUMATIC TUBE.

SPECIFICATION forming part of Letters Patent No. 651,175, dated June 5, 1900.

Application filed May 10, 1899. Serial No. 716,245. (No model.)

To all whom it may concern:

Be it known that I, GEORGE H. WOODMAN, a citizen of the United States, and a resident of New York, in Manhattan borough, county 5 and State of New York, have invented certain new and useful Improvements in Pneumatic Tubes, of which the following is a specification.

This invention consists in a pneumatic-tube 10 despatching-terminal embracing a self-closing door or gate for normally closing the opening in said terminal through which carriers are introduced for transmission, means for opening connections for supplying compressed air 15 to the despatch-tube rendered operative by the carrier in passing through said opening, means for enabling the carrier to be introduced for transmission in a direction opposite to the direction of its travel when it is moved 20 by the compressed air, and, finally, the combination therewith of means for automatically closing the connections for supplying compressed air to the despatch-tube when the carrier has completed its transit through the 25 despatch-tube.

While a lesser number than all of the above- 30 enumerated elements may be combined in a terminal productive of advantageous results without departing from the invention, when 35 assembled together a pneumatic tube may be thereby made wholly automatic in operation and a carrier may be received into the terminal by gravitation for transmission in a tube running upwardly from the terminal.

These improvements are especially applicable where great facility in despatching carriers is required—as, for example, in a store cash-service system, and in other places where groups of tubes are operated by one attendant.

In the accompanying drawings, illustrating the invention, Figure 1 is a side elevation of a terminal represented as standing in working position connected to the lower portion of 45 a despatch-tube and to the upper end of an air-supply pipe. Fig. 2 is a central vertical section thereof, showing all operative parts in their respective normal positions. Fig. 3 is a transverse section taken through the plane 50 intersected by the lines xx on Figs. 1 and 2 of the air-supply valve, valve-chamber, valve-operating diaphragm, diaphragm-chamber,

passage connecting the valve-chamber and the diaphragm-chamber, and the three-way cock interposed in said passage, showing said 55 valve, diaphragm, and cock in their normal positions. Fig. 4 is a longitudinal section of the three-way cock, its elongated stem, and adjacent operating-spindle and clutch. Fig. 5 is a transverse section taken through the 60 plane intersected by the lines yy on Fig. 4.

In the drawings the terminal A is represented as affixed to the counter B by the bolts aa . The despatch-tube C is represented as extending in an upward direction, having its 65 lower end inserted in the neck A' at the upper end of the terminal, where it opens into the chamber D, which is appropriately arranged to constitute an extension of the despatch-tube down to the opposite bottom wall 70 of the terminal. Connecting with the chamber D is the passage E for conducting the carrier into the chamber D when it has been introduced for transmission through the opening F, arranged in the upper wall of the terminal adjacent to the neck A'. The opening F has the flaring mouth f for facilitating the 75 introduction of carriers.

Provision is made for normally closing the opening F by a suitable self-closing gate or 80 cover, which may be the door F', arranged on the under side of said opening, appropriately to be swung open by an inpassing carrier, and made integral with or rigidly attached to the pin F², the ends of which extend laterally through the adjacent opposite 85 sides of the body of the terminal, wherein they are pivoted. The said door may be rendered self-closing and normally seated by the counterbalance-weight F³ or by any other suitable means of the nature required. The door 90 F' also performs the function of effecting the opening of connections for admitting compressed air to the despatch-tube after it has been moved to its open position by an inpassing carrier. It is important, therefore, to arrange said gate so that it will have a positive 95 range of motion. By the construction shown in the drawings its arrangement is such as to cause it to be opened by the weight of the 100 carrier and to compel it to be swung open by an inpassing carrier sufficiently to give it the range of motion required. In operation the carrier is placed endwise into the flaring

mouth f' , and then its impact on the gate F' causes the latter to swing open until the carrier passes by it, when it returns to its seated position. The carrier drops by gravitation 5 into the passage E , which is appropriately formed to deflect it into the lower end of the chamber D , where it assumes an upright position, ready for transmission up through the despatch-tube C in a direction opposite to its 10 delivery into the terminal.

Compressed air for propelling the carrier through the despatch-tube is admitted at the proper time to the lower end of the chamber D from the conduit G , which connects at one 15 end with the lower end of said chamber and at its other end with the air-supply valve H . The air-supply valve H is normally closed and is held in its closed position by the compressed air behind it in the valve-chamber I , 20 to which compressed air is constantly supplied from the compressed-air-supply pipe J , communicating with said valve-chamber and having a threaded connection with the lower neck A^2 of the terminal.

25 While the air-supply valve H may be adapted to be opened by the door F' through any suitable mechanical connections, it is preferred to open it by the action of compressed air under control of said gate. In the drawings, therefore, the stem H' of the air-supply valve H extends through the elastic diaphragm K , to which it is rigidly attached by means of the flanged head H^2 , secured to said diaphragm on the farther side thereof. The said diaphragm K is constituted to form a part of the 30 wall of the valve-chamber I and to have a larger surface area than that of the air-supply valve H , thus adapting it to move said air-supply valve off its seat when said diaphragm is permitted to be expanded under 35 the influence of the compressed air in said valve-chamber. Normally such expansion of said diaphragm is prevented, and it is maintained in its natural position by holding it balanced by an equal force of air-pressure exerted upon both sides of it. This is effected 40 by means of the passage i , which connects said valve-chamber with said diaphragm-chamber K' and which normally establishes communication 45 for the delivery of compressed air from the former to the latter. Means are provided for unbalancing the pressure upon said diaphragm to secure the opening of the air-supply valve. For this purpose the three-way 50 cock L is interposed in the passage i , which normally allows said passage to be open, but in the other position of its ports shuts off communication between the two said chambers and opens communication between said diaphragm-chamber and the escape-outlet L' , extending 55 through the shell of the three-way cock to the atmosphere. As soon as its ports are turned to the position last named the compressed air in said diaphragm chamber dis- 60 charges immediately into the atmosphere, and said diaphragm K then yields to the pressure of the compressed air in said valve-chamber 65

and by its expanding movement unseats the air-supply valve H . Compressed air then flows through the conduit G into the chamber D for despatching the carrier. The turning of said three-way cock may be effected by the movement of said door F' by the use of any appropriate arrangement of levers or other mechanism; but it is preferred to employ for 70 the purpose the spindle M and the connections shown in Figs. 1 and 4. The lower end of said spindle is tapered and stands loosely on end in the tapering socket L^2 , arranged in the top of the elongated stem L^3 of said three-way cock, affording support for said spindle and enabling it to rotate on its axis in one direction without imparting motion to said cock. Provision is made for rotating said spindle 75 in one direction and in the reverse direction by the opening and closing movement of the door F' , which is accomplished by suitable gearing connections—as, for example, the gearing connections between the upper end of said spindle and the adjacent end of the pin F^2 of said door. (Shown in Fig. 1.) During the opening movement of said gate the resulting partial rotation of said spindle does not alter the position of said cock; but said spindle does carry with it the clutch M' , loosely 80 connected to said spindle near the lower end thereof. The said clutch is adapted to be rotated with said spindle by means of the pin M^2 , extending from said spindle and resting in the vertical slot M^3 in the upper end of said clutch, the said slot being sufficiently 85 elongated to permit said clutch to move vertically on said spindle. It is the function of the clutch M' to effect the locking of said spindle to said three-way cock when said spindle has been rotated in one direction by 90 the opening movement of the gate F' and by this means to enable said door by its closing movement and the resulting rotation of said spindle in the reverse direction to turn 95 said three-way cock to the position required to occasion the opening of the air-supply valve H . For locking said clutch to said three-way cock the under end of said clutch and the upper opposed end of the elongated 100 stem of said three-way cock are provided with certain mutually-related dogs and intervening spaces, the said dogs m of said clutch resting normally upon the upper surfaces of the dogs l of said stem. When said clutch is rotated, with said spindle, to the position reached when the door F' becomes fully 105 opened, the dogs m of said clutch are then in juxtaposition to the spaces between the dogs l of said stem, and vice versa, and said clutch then drops by gravity, bringing said dogs and spaces into mutual engagement. The closing movement of said door then turns 110 said three-way cock so as to effect the opening of the air-supply valve H . The means 115 used for rendering the door F' self-closing are sufficient also for imparting the necessary force for effecting the actuation of said three-way cock. The air-supply valve H having 120

been opened in the manner stated, compressed air continues to be delivered to the despatch-tube until said clutch becomes disengaged from its locking position with said three-way 5 cock. It becomes so disengaged by lifting it sufficiently on said spindle to free said dogs from their mutually-related spaces, and thereupon said three-way cock is returned to its normal position by the expanding force of the 10 clock-spring L⁴, wound around the base of said elongated stem and fastened at its inner end to said stem and at its outer end to the adjacent post L⁵, extending upwardly from the shell of said three-way cock. The post L⁵ 15 also serves as a stop for maintaining said three-way cock in its normal position. As soon as said three-way cock is thus returned to its normal position compressed air flows from the valve-chamber I to the diaphragm- 20 chamber K', and the elastic diaphragm K then becomes free to contract and assume its normal position, concurrently closing the air-supply valve H. The said clutch may be manually disengaged from its locking position, or 25 any appropriate automatic releasing device may be used for the purpose. It is preferred, however, to employ the time tripping apparatus shown in the drawings and more particularly described and claimed in my application 30 for patent Serial No. 709,377, consisting in the present case of the retarding-transmitter N, (preferably a leather diaphragm,) arranged in the conduit N', which connects at one end with the passage E of the terminal and at the 35 other end with the working chamber O of the flexible diaphragm P. When the air-supply valve H is opened, compressed air passes from the passage E into the conduit N' and then is slowly delivered by permeation through the 40 retarding-transmitter N to said working chamber O, causing the gradual expansion of said flexible diaphragm P and the consequent slow outward movement of the follower Q until the latter engages with and moves the adjacent 45 arm R of the bell-crank lever R' sufficiently to raise its upper arm R² until the forked extensions R³ R³ thereof by their impact against the under side of the check-nut M⁴, arranged on the clutch M', lift said clutch out of its 50 locking position. Upon the resulting closing of the air-supply valve H the supply of compressed air to the working chamber O ceases, and the follower Q and the flexible diaphragm P are returned quickly to their normal positions 55 by the spring Q' as the compressed air in the working chamber O is rapidly discharged from the check-valve S into the passage E, from which it finds escape into the despatch-tube. The position of the adjustable check-nuts M⁴ M⁴ on the clutch M' determines the 60 range of the operative stroke of the follower Q, and hence regulates the timing of the trip, which is arranged to occur when the carrier has completed its journey through the despatch-tube. 65

It will be perceived that the organization of the terminal shown in the drawings per-

mits the gate to effect the opening of the air-supply valve by the exercise of very little force, the small three-way cock being turned 70 with very little frictional resistance and the much greater force required to unseat the air-supply valve being furnished by the compressed air, and, further, that arranging the gate by its closing movement to cause the 75 opening of the air-supply valve permits the gate to open and close without occasioning any blast of air to escape through the opening for receiving the carrier and allows the carrier to drop by gravity into its position for 80 transmission before it is acted upon by the compressed air.

The important advantage of enabling the carrier to be introduced by gravitation for transmission in a tube running upwardly from 85 the terminal arises from the fact that in large plants of pneumatic tubes the central stations are usually located in the basements of the buildings, rendering it impossible for the tubes to run downwardly from the terminals, 90 and from the further fact of the inconvenience in pneumatic tubes operated by compressed air of inserting a carrier in an upward direction in a despatch-tube opening downwardly and of then closing a gate under the carrier, 95 as has heretofore been required. It is obvious, however, that the terminal herein described is not limited in its application to a despatch-tube running upwardly from the terminal, as the opening at the upper neck A' may be closed 100 and the end of the tube may be inserted in the lower end of the chamber D, and the tube may then run downwardly from the terminal. The usefulness of this form of terminal is further illustrated by the fact that several of 105 them may be attached to the same despatch-tube at intervals apart, affording a number of sending-stations on one line of tube. This results partly from the formation of the terminal, adapting the chamber D to constitute 110 a continuation of the despatch-tube by connecting the tube at each end thereof, and more particularly from the organization of the door, which, being inwardly opening and normally closed, prevents any escape of air when compressed air exists in the despatch-tube. 115

The organization of the door F' is not limited to such an arrangement of it as will enable the weight of the carrier alone to open it, as it is obvious that it may be made to 120 offer some resistance to the carrier, requiring for opening it a manually-exerted impulse to be given to the carrier when it is placed endwise against the door without detracting appreciably from the facility afforded for despatching carriers. 125

What is claimed as the invention is—

1. In a compressed-air-operated pneumatic-despatch-tube system wherein the air-current acts only during the transmission of the carrier, a despatching-terminal having an opening for the admission of carriers for transmission, a door for closing said opening and mechanical devices for acting upon said

- door for closing it and holding it normally closed against the passage of air.
2. A pneumatic-despatch tube, a self-closing compressed-air-supply valve for controlling the supply of compressed air to said tube, a yieldable and self-returning carrier-operated trip arranged in the path of the carrier, and connections between said trip and said valve for effecting the opening of said valve by the actuation of said trip.
3. In a pneumatic-tube apparatus, the combination with a compressed-air-operated supply-valve, of means operated by a carrier for controlling the opening of said supply-valve.
- 15 4. In a pneumatic-tube apparatus, the combination with a self-closing compressed-air-operated supply-valve of means operated by a carrier for controlling the opening of said supply-valve.
- 20 5. In a pneumatic-tube despatching-terminal, a self-closing door for normally closing the opening provided therein for introducing the carrier for transmission, and an air-supply valve for admitting compressed air for despatching the carrier, and connections between said door and air-supply valve whereby the supply-valve is opened by the movement of said door.
- 25 6. A pneumatic-tube despatching-terminal having a self-closing door for normally closing the opening in said terminal through which the carrier is introduced for transmission in the despatch-tube to which said terminal is attached, and having means under the control of said door for opening connections for supplying compressed air for despatching the carrier in said despatch-tube.
- 30 7. A pneumatic-tube despatching-terminal provided with an opening for entering the carrier therein for transmission through the despatch-tube to which said terminal is attached; a self-closing door for normally closing said opening; connections for supplying compressed air for despatching the carrier; a valve for controlling the supply of compressed air; and means for effecting the opening of said valve made operative by the movement of said door.
- 35 8. A pneumatic-tube despatching-terminal provided with an opening for entering the carrier therein for transmission through the despatch-tube to which said terminal is attached; a self-closing door for normally closing said opening; connections for supplying compressed air for despatching the carrier; a valve for controlling the supply of compressed air; means for effecting the opening of said valve made operative by the movement of said door; a stop for maintaining said valve in its open position; and a releasing device for disengaging said stop from its holding position.
- 40 9. A pneumatic-despatch tube; connections for supplying compressed air thereto; an opening for receiving carriers for transmission through said tube; a self-shutting door for closing said opening adapted to be opened by the passage of a carrier through said opening; a valve for controlling the supply of compressed air and connections between said valve and said door as and for the purpose set forth.
- 45 10. A despatching-terminal connected with a pneumatic-despatch tube; an opening for receiving carriers for transmission through said despatch-tube; a self-shutting door for normally closing said opening and connected to move inwardly by the passage of a carrier through said opening; a valve for controlling the supply of compressed air and connections between said valve and door whereby the valve is opened by the movement of said door.
- 50 11. In a pneumatic-tube despatching-terminal, an opening therein for receiving carriers for transmission; a normally-closed and self-closing door hinged to be swung out of its closed position by the thrust of a carrier manually introduced through said opening; a valve for admitting compressed air for despatching the carrier and connections between the valve and door whereby the valve is opened by the movement of said door.
- 55 12. In a pneumatic-tube despatching-terminal, an opening therein for receiving carriers for transmission; a normally-closed and self-closing door yieldable to open inwardly under the weight of an inpassing carrier; and a valve for admitting compressed air for despatching the carrier and connections between the valve and door whereby the valve is opened by the movement of said door.
- 60 13. In a pneumatic apparatus a despatch-tube; connections for supplying compressed air thereto; a valve for controlling the supply of compressed air; an opening for receiving carriers to be transmitted through said despatch-tube; a normally-closed and self-closing door arranged on the under side of said opening and adapted to be swung open by a carrier introduced through said opening; and means adapting the closing movement of said door to effect the opening of said air-supply valve.
- 65 14. In a pneumatic apparatus, a valve for controlling the flow of compressed air from a compressed-air-supply conduit; a piston; connections between said valve and said piston for enabling said valve to be unseated by the operative stroke of said piston; means for normally maintaining a balanced air-pressure upon the opposite sides of said piston; and means for releasing the air-pressure from one side of said piston for the purpose of enabling the compressed air on its other side to effect its said operative stroke.
- 70 15. A pneumatic-tube despatching-terminal having an opening for the introduction of carriers therein by gravitation, and a pneumatic tube for despatching said carriers connected to the upper portion of said terminal, and running in an upward direction therefrom.

16. A pneumatic-tube despatching-terminal having an interior chamber for receiving carriers to be transmitted through a despatch-tube connected to the upper end of said chamber, and an opening in said terminal for the introduction of carriers to be delivered by gravitation into said chamber.

17. A pneumatic-tube despatching-terminal having an interior chamber in alinement with a despatch-tube connected to the upper end of said chamber; a passage connecting with said chamber for deflecting carriers into said chamber; and an opening in said terminal above said passage for the introduction of carriers into said passage.

18. The combination with a despatch-tube, an inlet for the propelling-air, a valve therein and a transmitter, of a self-closing door for said transmitter located between the inlet-
20 mouth thereof and the inlet for the propelling-air, said door being connected to said valve.

19. In a pneumatic-tube despatching apparatus, a chamber for receiving carriers to be despatched, an oblique passage connecting with said chamber, connections for supplying compressed air to said chamber, a valve for controlling the supply of compressed air, and a carrier-operated trip arranged across the path of travel of said carriers in said oblique passage for effecting the opening of said valve. 25

20. In a pneumatic-tube despatch-terminal, a self-closing door for normally closing the opening provided therein for introducing the carrier for transmission, and an air-supply valve for admitting compressed air for 35 despatching the carrier designed to be opened by the movement of said door.
